CABINET FOR TELEVISION RECEIVER SETS

William M. Evans, Columbus, and Beverley H. Moseley, Jr., Grove City, Ohio, assignors to RadiOhio Incorporated, Columbus, Ohio, a corporation of Ohio

Filed June 25, 1963, Ser. No. 75,509

Term of patent 14 years

(Cl. D56—4)

FIG. 1 is a perspective view of a cabinet for television receiver sets showing our new design;

FIG. 2 is a top plan view;

FIG. 3 is a side elevational view on a slightly enlarged scale; and

FIG. 4 is a front elevational view thereof on the same scale as FIG. 3.

We claim:

The ornamental design for a cabinet for television receiver sets, substantially as shown.
